UNITED STATES PATENT OFFICE

HARRY H. STRAUS, OF NEW YORK, N. Y.

CIGARETTE PACKAGE

Application filed October 12, 1929. Serial No. 399,204.

This invention relates to an improved package made up of thin fibrous material with little or no inherent stiffness such as paper, thin cardboard, tinfoil or a combination of these and has for an object to combine with such package a stiffener made of cardboard or similar material which will serve to stiffen the package or container to prevent distortion thereof and injury to the 10 contents, and is at the same time so shaped and cut and combined with the package and contents thereof as to form a convenient means to aid in tearing an opening in the package which will possess a regular configuration pleasing to the eye and a convenient means for extracting the contents.

Articles which are sold for a nominal price are often placed in paper packages which 20 insufficiently protect the articles themselves against crushing or other forms of distortion. For instance, in packaging the more popular brands of cigarettes, a paper and tinfoil cover is used to protect the contents. When the package is full, and before it is opened, 25 the cigarettes themselves, because they are tightly bundled together offer some resistance to crushing and distortion, but even under these conditions this resistance is not very great and often the contents are crushed or broken before the package is opened. After part of the contents have been removed the resistance of the tightly packed bundle is reduced to the resistance of a few loosely packed cigarettes in a paper cover and the 35 remainder of the cigarettes are often either partly or wholly crushed before they may be entirely consumed by the user.

Because of this undesirable condition, certain manufacturers have been quite successful in marketing stiff leather receptacles for receiving a package of cigarettes and which serve to protect the cigarettes until the last one is consumed, but these receptacles are 40 heavy and inconvenient to carry and use.

Manufacturers of the more expensive brands overcome this difficulty by selling their cigarettes in cardboard boxes, but these 45 boxes are too expensive to be commercially practicable for the more popular brands, and 50 so it is still a further object of this inven-

tion to combine with a cheap, light weight paper package a stiffening means which will be inexpensive to produce and apply to the package and which will furnish sufficient resistance to preserve the contents of the package until the contents are entirely consumed. 55

I have shown my invention as embodied in a package of cigarettes but do not wish to be limited to cigarettes or tobacco products, inasmuch as this particular style of package 60 may be utilized for many commodities.

I have also shown the aperture or opening in one corner of the package as this seems to be a convenient way of extracting the cigarettes, but I wish it to be understood that 65 some other part of a package may be torn off if desirable when this invention is used with other commodities.

Further features and objects of the invention will be more fully understood from the 70 following detail description of the accompanying drawing, in which

Fig. 1 is a perspective view of a package of cigarettes embodying my invention and closed and sealed as it would be sold to a 75 retail customer in a tobacco shop.

Fig. 2 is a perspective view illustrating the removal of the corner of the package by utilizing the cardboard stiffening member 80 embodied therein.

Fig. 3 is a perspective view of the package after one corner thereof has been removed.

Fig. 4 is a perspective view of the stiffening member itself which is adapted to be placed 85 between the outside covering of the package and the tinfoil wrapper of the cigarettes.

Fig. 5 is a front elevation with part of the outside covering cut away to show the relative position of the tin-foil covering, stiffening member and outer cover. 90

Looking at the drawing and especially at Fig. 1, P illustrates a package of cigarettes embodying my invention and comprising an outer covering 2, a stiffening member 3, and a tinfoil inner cover 4 with the usual revenue stamp 5 placed so as to seal the package or container. 95

The cigarettes are wrapped in the tinfoil 100 cover 4 in the usual manner but as this process

forms no part of the present invention it will not be described.

Upon the outside of the tinfoil cover a stiffener 3 is placed. This stiffener may be made of a light cardboard for instance, and comprises a bottom portion 7 of the same length as the length of the bottom of the package of cigarettes, two side wall portions 8 and 9 turned up therefrom and a top portion 10. As will be seen in Fig. 4, the top of side portion 8 is cut diagonally downward from an upper corner thereof, as shown along line 12. Top portion 10 is not as long as the bottom portion 7 and will extend only part way across the top of the package of cigarettes. As best shown in Figs. 2, 3 and 5, it extends a trifle more than half way across. After the stiffening member is applied around the tinfoil cover 4, the outer covering 2 is applied around the tinfoil cover 4, the outer covering 2 is applied to the outside of the tinfoil cover and stiffening member. This outer covering is usually made of paper and has printed thereon information such as names, trademarks, guarantees, and instructions.

Finally, after the application of the outside cover 2 the revenue stamp 5 is applied to seal the tinfoil cover, stiffening member and outer cover in place. The outer cover 2 is similar to the covers now in use for packaging cigarettes except that one corner thereof, such as the upper corner nearest to the observer, as seen in Fig. 1, is cut away by removing a triangular piece from the upper left hand corner of the front side of cover 2 and an adjacent triangular piece from the upper right hand corner of the adjacent side which is illustrated in Fig. 1. This would mean the removal of a triangular notch from the cover 2 when it is in sheet form before application to the package of cigarettes.

The purchaser of the package may open the tinfoil cover to make an aperture in the package by lifting flap 15 and tearing through revenue stamp 5 to edge 16 of the stiffener 3, then forwardly along edge 16 to the front upper edge of the package as viewed in the drawing and down line 13 to its junction with line 12. Flap 17 is now uncovered and may be lifted and torn backwardly through the revenue stamp along edge 16 to rear edge 18 and then along edge 18 to line 12 and down line 12 to line 13 where the tinfoil may be entirely disengaged. Of course there are other ways of removing this tinfoil cover and I have described only one convenient method.

The stiffening member is also advantageous in holding in place the cigarettes which are packed between top 10 and bottom 7 after the package has been opened and the cigarettes immediately below the opening removed because the remaining cigarettes stay wedged between the flap 10 and bottom 7 and will not slide out under the opening to be lost or broken. In fact a sharp tap is generally

necessary to loosen the cigarettes sufficiently to allow them to fall out and by proper regulation of the intensity of the tap one or two cigarettes may be disengaged to fall forward to the opening while the remainder stay in place under the top 10 when they are fully protected.

The result of this construction is a cigarette package or container of sufficient stiffness and strength to prevent distortion of the cigarettes before the package is opened and after it has been opened, but in addition means are provided for enabling the purchaser to quickly and easily make a neat and convenient opening for removal of the cigarettes without entirely opening up one side of the package, but instead only a part of one side so that sufficient of the package and stiffener is retained to protect the cigarettes even until the last one is consumed.

Whereas, I have described my invention by reference to specific forms thereof, it will be understood that many changes and modifications may be made without departing from the spirit of the invention.

I claim:—

1. A package comprising in combination material possessing little inherent stiffness, said material extending substantially about four sides and the top end of the package, stiffening member associated with and on the exterior of said material and extending at one side, thence across the bottom, thence at another side, and thence from one edge of the top end toward but spaced from the opposite edge of the top end, the terminal edge of said stiffening member at one side, extending at an angle to the direction of extension of said opposite edge of the top end, said terminal edge serving to define the path of tearing of said material of little inherent stiffness when torn by grasping the same adjacent said opposite edge, and means for securing said stiffening member to said material of little inherent stiffness.

2. A package comprising in combination material possessing little inherent stiffness, said material extending substantially about four sides and the top end of the package, stiffening member associated with and on the exterior of said material and extending at one side, thence across the bottom, thence at another side, and thence from one edge of the top end toward but spaced from the opposite edge of the top end, the terminal edge of said stiffening member at its top end portion being substantially parallel to said opposite edge, said terminal edge serving to define the path of tearing of said material of little inherent stiffness when torn by grasping the same adjacent said opposite edge, and means for securing said stiffening member to said material of little inherent stiffness.

3. A package comprising in combination material possessing little inherent stiffness,

said material extending substantially about four sides and the top end of the package, stiffening member associated with and on the exterior of said material and extending at 5 one side, thence across the bottom, thence at another side, and thence from one edge of the top end toward but spaced from the opposite edge of the top end, the terminal edge of said stiffening member at one side, 10 extending at an angle to the direction of extension of said opposite edge of the top end, said terminal edge serving to define the path of tearing of said material of little inherent stiffness when torn by grasping the 15 same adjacent said opposite edge, and material possessing little inherent stiffness surrounding and securing said stiffening member.

4. A package comprising in combination 20 material possessing little inherent stiffness, said material extending substantially about four sides and the top end of the package, stiffening member associated with and on the exterior of said material and extending at 25 one side, thence across the bottom, thence at another side, and thence from one edge of the top end toward but spaced from the opposite edge of the top end, the terminal edge of said stiffening member at its top end portion 30 being substantially parallel to said opposite edge, said terminal edge serving to define the path of tearing of said material of little inherent stiffness when torn by grasping the same adjacent said opposite edge, and 35 material possessing little inherent stiffness surrounding and securing said stiffening member.

In testimony whereof I have signed this specification this 10th day of October, 1929.

40 HARRY H. STRAUS.
